UNITED STATES PATENT OFFICE.

ALBERT C. BRAGG, OF ORANGE, MASSACHUSETTS, ASSIGNOR OF TWO-THIRDS
TO THE NEW HOME SEWING MACHINE COMPANY AND AMOS E. EMERY,
OF SAME PLACE.

COMBINED TICKET-HOLDER AND ADVERTISING MEDIUM.

SPECIFICATION forming part of Letters Patent No. 600,848, dated March 15, 1898.

Application filed October 16, 1896. Serial No. 609,096. (No model.)

To all whom it may concern:

Be it known that I, ALBERT C. BRAGG, a citizen of the United States, and a resident of Orange, Franklin county, State of Massachusetts, have invented a new and useful Combined Ticket - Holder and Advertising Medium, of which the following description, taken in connection with the drawings here-with accompanying, is a specification.

10 My invention has for its object to provide a device of simple construction and attractive appearance that may be located in railway-cars or other public conveyances upon the back of the seats or in other conspicuous and
15 convenient positions within reach of the passengers, having means for receiving a passenger's ticket and holding the same in a convenient position to be taken by the conductor or fare-taker, and also having means in combination with such ticket-holding means for supporting and exposing an advertising card or medium. This object I secure by means of the construction and arrangement of parts hereinafter set forth in detail and pointed out
25 in the claims.

Referring to the drawings, Figure 1 represents a section of the back of a car-seat with a device embodying my invention secured thereon. Fig. 2 is a vertical section through
30 the same; and Figs. 3 and 4 represent a face view and a vertical section, respectively, of a device embodying my invention in a slightly different form from that shown in Figs. 1 and 2.

35 To explain in detail, *a* represents a section of the back of a car-seat, on which, as herein illustrated, a device embodying my invention is secured. This device, as shown in Figs. 1 and 2, consists of two plates *b* and *b'*, supported in close position to each other, whereby their inner or adjacent faces will impinge and hold a ticket when inserted between the same, as clearly shown in said Figs. 1 and 2, in which *c c* represent tickets. The adjacent or
40 ticket-impinging surfaces of these holding-plates *b* and *b'* are preferably in a convex form, as shown in Fig. 2, so that a widened mouth or space is formed between the same at the upper and lower sides thereof, whereby
45 a ticket may be more readily inserted be-

tween the plates from either said upper or lower side and the ticket be impinged at a central point between the same. Another feature of the rear plate *b* being formed with a convex outer face or having its upper and 55 lower edges turned backwardly is that when the device is secured to a seat or other object the edges of said plate will be forced closely against or into the upholstery or other material, as shown in Fig. 2, and thus prevent possibility of the ticket being inserted behind the said plate or in other than its proper place between the two plates.

The front ticket-holding plate *b'*, as herein shown, is formed with its upper and lower 65 edges bent slightly forward, as at *b³* *b³* in Fig. 2, against which and over the front of the plate *b'* is secured a plate *d*, the plate *b'* being concave on its forward side and having the projecting edges *b³* *b³*, against which the 70 plate *d* abuts, thereby forming a space or chamber between the said plates, in which an advertising-card, as represented at *e* in Fig. 1, or other desired advertising medium, may be secured and be exposed through an opening 75 in the plate *d*, as clearly shown, which opening, if so desired, may be protected by glass or other transparent material.

The plates *b*, *b'*, and *d* may be secured together and in position upon the back of a car-seat, as shown, or in any other desired place by any suitable means, the means, as herein shown, being two screws *f f*, which pass through the several plates and into the seat, as in Fig. 2.

80 The advantages of such a device as described, both for its convenience to the passengers in affording a convenient means for holding their ticket and to the conductor or fare-taker in having the tickets in a convenient place to be received or taken by him, and also the great value of the same as an advertising medium in supporting and exposing cards or other advertising means in a conspicuous position before the passengers, will 85 be obvious.

90 Referring to Figs. 3 and 4, I have illustrated my invention in a slightly different form from that shown in Figs. 1 and 2. In this instance in lieu of employing two separate ticket-hold- 95
100

ing plates, as before described, whereby a ticket may be inserted between the same from either above or below, I have used a single plate *h*, which is folded or turned back upon itself, so as to form two oppositely-located plates corresponding to the plates *b* and *b'* of Figs. 1 and 2, which are united at their lower edge, and thus form a pocket or ticket-receptacle which is only open at the top, as shown in Fig. 4. In this construction the advertising-card is supported between the forward side of the plate *h* and a plate *d*, secured thereon, as in Fig. 1. The forward side or part of the plate *h*, as herein shown, is preferably formed with its upper edge *h'* turned forward and with a forwardly-projecting rib *h²* adjacent to the lower edge of the plate *d*, which forwardly-projecting parts form a space between which the advertising-card is held from vertical displacement.

Having thus illustrated and described my invention as embodied in two different forms, I do not wish to be understood as confining myself to the particular construction as shown, as it will be obvious that the same may be more or less materially modified without departure from my invention. For instance, the rear plate *b* might be dispensed with, if so desired, and the ticket be inserted between the plate *b'* and the back of the seat or other object to which it is secured, or the form or arrangement of the several parts be also more or less modified without departure from my invention.

Having thus set forth my invention, what I claim as new, and desire to secure by Letters Patent of the United States, is—

1. A combined ticket-holder and advertising medium, consisting of two plates support-

ed adjacent to each other to receive and hold 40 a ticket between the same, one of said plates being provided with an outwardly-turned edge whereby a broadened or enlarged mouth is formed to more readily receive a ticket between the plates, and a third plate supported 45 adjacent to one of said ticket-holding plates with a space between the same to receive an advertising card or medium, and provided with an opening therein to expose the latter, substantially as and for the purpose set forth. 50

2. A combined ticket-holder and advertising medium, consisting of two plates supported adjacent to each other to receive and hold a ticket between the same, one of said plates being provided with two outwardly-extended 55 projections, and an additional or third plate supported against said projections on the ticket-holding plate whereby a space or chamber is formed between the same to receive an advertising card or medium, and provided with an opening therein to expose the latter, substantially as and for the purpose set forth. 60

3. A combined ticket-holder and advertising medium, consisting of two oppositely-located plates supported adjacent to each other 65 to receive and hold a ticket between the same and having their lower edges united, and an additional plate supported adjacent to one of said ticket-holding plates with a space between the same to receive an advertising 70 card or medium, and provided with an opening therein to expose the latter, substantially as and for the purpose set forth.

ALBERT C. BRAGG.
